UNITED STATES PATENT OFFICE.

DANIEL BENJAMIN STEVENS, OF TORONTO, CANADA.

DESIGN FOR A MASSAGE INSTRUMENT.

SPECIFICATION forming part of Design No. 32,665, dated May 15, 1900.

Application filed March 8, 1900. Serial No. 7,935. Term of patent 7 years.

To all whom it may concern:

Be it known that I, DANIEL BENJAMIN STEVENS, a subject of the Queen of Great Britain, residing at the city of Toronto, in the 5 county of York, in the Province of Ontario, Canada, have invented and produced a new and original Design for a Massage Instrument, of which the following is a specification, reference being had to the accompanying drawings, forming part thereof.

Figure 1 is a perspective view of the design. Fig. 2 is a perspective view showing the device reversed.

As shown in the drawings, the leading or 15 material feature of my design consists of a

base A, provided with an arc-shaped handle B, a protecting-cap C, and the divided bottom plates D, rounded off at the outside edges at d, as indicated.

I claim—

20

The design for a massage instrument as herein shown and described.

In testimony whereof I have signed my name to this specification in the presence of two subscribing witnesses.

DANIEL BENJAMIN STEVENS.
